US00D984385S

(12) **United States Design Patent** (10) Patent No.: **US D984,385 S**
(45) Date of Patent: **** Apr. 25, 2023**

(54) **EQUIPMENT FOR DISTRIBUTION OF ELECTRIC POWER**

(71) Applicant: **LG ELECTRONICS INC.**, Seoul (KR)

(72) Inventors: **Hewon Kihl**, Seoul (KR); **Yongho Lee**, Seoul (KR); **Hyunhee You**, Seoul (KR)

(73) Assignee: **LG ELECTRONICS INC.**, Seoul (KR)

(**) Term: **15 Years**

(21) Appl. No.: **35/512,850**

(22) Filed: **May 3, 2021**

(80) **Hague Agreement Data**

Int. Filing Date: **May 3, 2021**

Int. Reg. No.: **DM/215009**

Int. Reg. Date: **May 3, 2021**

Int. Reg. Pub. Date: **Nov. 5, 2021**

(30) **Foreign Application Priority Data**

CLAIM

The ornamental design for an equipment for distribution of electric power, as shown and described.

DESCRIPTION

1. Equipment for distribution of electric power

1.1 : Perspective

1.2 : Front

1.3 : Back

1.4 : Left

1.5 : Right

1.6 : Top

1.7 : Bottom

The broken lines indicate portions of the article that form no part of the claimed design.

1 Claim, 7 Drawing Sheets
